UNITED STATES PATENT OFFICE.

JOHN HOWARD McCORMICK, OF NEW ORLEANS, LOUISIANA, ASSIGNOR OF
ONE-HALF TO WILLIAM MEADE MONTGOMERY, OF SAME PLACE.

MAIL-BAG LOCK.

SPECIFICATION forming part of Letters Patent No. 351,063, dated October 19, 1886.

Application filed April 26, 1886. Serial No. 200,169. (No model.)

To all whom it may concern:

Be it known that I, JOHN HOWARD McCORMICK, a citizen of the United States of America, residing at New Orleans, in the parish of Orleans and State of Louisiana, have 5 invented certain new and useful Improvements in Mail-Bag Locks, of which the following is a specification, reference being had thereto to the accompanying drawings.

10 My invention relates to mail-bag locks; and it consists in a lock or fastener for the cords of mail-bags, the peculiar features of which will be fully understood from the following description, when taken in connection with the 15 annexed drawings.

Figure 1 is a perspective view of my improved lock, showing a cord applied to it. Fig. 2 is a longitudinal central section of the lock, showing a cord gripped in it by one of 20 the levers or dogs. Fig. 3 is a top view showing the interior of the lock-case. Fig. 4 is a view of the key. Fig. 5 shows the device applied to a bag.

Referring to the annexed drawings by letters, A designates the case of the lock, which 25 is preferably rectangular and constructed with a pillow, G, leaving a depression, a. It is also constructed with a receptacle, R, adapted to receive and hold a tag or card, S.

30 E E designate two curved gripping dogs or levers, which are free to rock on a transverse fulcrum-pin, A', and which are curved somewhat resembling the italic letter *f*. Directly over the flat surface of the pillow G the enlarged 35 gripping ends of the levers are serrated, as indicated at I, and at the opposite depressed ends of these levers are slight rounded lugs or wards K K. In the same planes with and near the lugs or wards K K are studs F F, 40 fixed to the levers. The object of the studs and wards above described is to allow the notched bit of the key P to pass them in the

act of unlocking or freeing the cord or rope M from the gripping ends of the levers K K.

B designates the key-hole through one side 45 of the lock-case, directly opposite which is a capped key-barrel seat, H.

The stepped cone L (shown in Fig. 3) is designed to receive the steps shown on the key in Fig. 4.

50 By reference to Fig. 2 it will be seen that the cord or rope M is passed through apertures C, beneath the long arms of levers K, between the serrated gripping ends of said levers and the pillow G, and out of the case 55 through apertures C'. The cord is thus bent or deflected out of a straight line in its course through the lock-case.

I am aware that serrated gripping dogs or levers, in combination with cases, have been 60 used before my invention for mail-bag-rope fasteners, and I do not therefore claim such devices, broadly.

What I do claim as new is—

1. A mail-bag lock consisting of a case having 65 a pillow, G, and a depression, a, a key-hole, and perforations for the passage of a cord, in combination with curved levers provided with serrations, substantially as described.

2. The combination, in a mail-bag lock, of 70 the case A, constructed with a tag-receptacle, a pillow, G, a depression, a, a key-hole and key-barrel cup, gripping-levers E E, fulcrumed at A', and provided with wards K K, studs F F, and serrated gripping ends, and the cord-apertures through the ends of the case, all constructed and adapted to operate substantially 75 in the manner and for the purposes described.

In testimony whereof I affix my signature in presence of two witnesses.

JOHN HOWARD McCORMICK.
